R. KRONENBERG.
COMBUSTION MOTOR.
APPLICATION FILED AUG. 25, 1919.

1,373,337.

Patented Mar. 29, 1921.

UNITED STATES PATENT OFFICE.

RUDOLF KRONENBERG, OF OHLIGS, GERMANY.

COMBUSTION-MOTOR.

1,373,337.

Specification of Letters Patent. Patented Mar. 29, 1921.

Application filed August 25, 1919. Serial No. 319,853.

To all whom it may concern:

Be it known that I, RUDOLF KRONENBERG, a citizen of Germany, residing at No. 31 Wilhelmstrasse, Ohligs, Rhenish Prussia, 5 Germany, have invented certain new and useful Improvements in Combustion-Motors, of which the following is a specification.

My invention relates to an improved combustion-motor and the object of this improvement is to provide a motor so constructed, that the cooling is entirely performed by air and any water-cooling may 10 be quite dispensed with, or, in particular cases, reduced to a minimum.

It has already been tried, with motors of a smaller kind, to perform the cooling alone by air, but the results have failed to give full satisfaction.

20 The present invention, however, tends to attain this scope even with combustion-motors of a larger size; my invention, accordingly, is particularly applicable in motors for propelling automotive vehicles and 25 aero-planes.

The principal idea of my invention consists in conducting the cooling atmosphere to the inside surface of the hollow piston, to such extent, that it comes into intimate 30 contact with the bottom of the piston and also with its sides about the packing. The simplest mode of realizing said purpose consists in employing a piston open at the outside end extending into the cylinder of 35 the motor in a known manner but without any guiding members, the said piston being externally connected to the crank and containing no gearing of any kind inside its hollow space, thus allowing to the atmosphere to directly enter into the piston without any impediment and to freely make 40 contact with the entire area of the hollow inside of the piston. In this manner and without the aid of any further means an intensive cooling of the piston is obtained 45 and especially in that place where it is most required, as all parts have been removed from that place, which could have the effect of impairing the free access of the atmosphere.

50 The operative effect of the cooling will be much enhanced, still, if a stationary member, the so-called displacer, is arranged to project into the hollow space of the piston, so as to partly obstruct the area of the hollow space but which helps to accelerate 55 the motion of the atmosphere, thereby ac-

celerating the change of air especially in the proximity of the walls of the piston.

In the case where a plurality of cylinders are employed for working the motor, it is 60 preferable to arrange the said cylinders one behind another.

In employing a motor driven by a plurality of cylinders, the four stages of which are distributed among four cylinders axially arranged one behind another and the pistons of which four cylinders are simultaneously acting on a single crank-shaft, it is particularly advantageous to connect the hollow pistons of said cylinders singly to 70 a single connecting-rod passing through laterally, which is working on the crank-shaft. In such case the reciprocating motion of said connecting-rod will call forth an agitation of the atmosphere which promotes the exchange of air within the hollow spaces of the single pistons, the more so, if a displacer extends into said pistons, 75 as before described. Besides this advantage, the whole arrangement of the four cylinder-motor will be improved by greater simplicity and by greater facility in being overlooked, also by a reduction of repairs 80 becoming necessary.

In the accompanying drawings I have 85 illustrated in—

Figure 1 a motor having but a single cylinder constructed according to my invention.

Fig. 2 shows the modification above referred to of a hollow piston having a displacer extending into its interior.

Fig. 3 serves to explain a detail of Fig. 2.

Fig. 4 discloses the arrangement of a four-cylinder motor having the pistons of 95 the four cylinders connected to each other by a lateral reciprocating connecting rod.

In the said four figures of the drawings all parts have been left away which do not refer to the essential features of my invention; particularly the whole mechanism of the distribution, including the valves for feeding the fuel and the mixture of gas and air, and parts connected therewith, have been left away.

Referring to the drawings, *b* designates the hollow piston open to the outside, which piston reciprocates within the cylinder *a* and carries near its open head lateral lugs *c*, *c*, engaged by the forked connecting-rod 110 *d*. Said lugs *c*, *c* traverse lateral slots *r*, *r*, of extensions of the wall of the cylinder.

The opposite end of said forked connecting-rod is engaged by the crank f of a shaft which carries the fly-wheel p .

By the motion of the crank and the fly-wheel a draft of air is called forth, which acts to perform an exchange of air within the hollow piston b and brings the fresh air into contact with the totality of the wall of the piston and particularly with the closed bottom of the piston, as also with the outside of the piston-wall carrying the packing, the inside of the piston being entirely free of any gearing. The motion of the vehicle helps to enhance the draft of air and its ex-
15 changing action for cooling the piston.

Fig. 2 represents that modification of my invention in which a displacing body h extends into the hollow of the piston b , the said body h being, for instance, fixed stationary to the head of the extension of the wall of the cylinder. In the drawings the said body has been shown screwed on to a cover-plate i , open-worked and seated on the extension of the cylinder. Fig. 3 shows the said cover-plate i in side-elevation. Through the perforations k of said plate the outside air may freely pass into the hollow piston b , the displacing body h acting in favor of the exchange of air by vigorously forcing the air
20 against the inside surface of the walls of the piston. When the said piston is moving outward, the displacer h will act to dispel the major part of the air out of the piston, while on moving inward of the piston,
25 fresh air will be drawn in by suction. The said displacer h , preferably, is equally formed hollow and open to the outside for permitting air to enter into said displacer.

In Fig. 4 I have shown a four-cylinder motor constructed in the manner above pointed out.

a^1, a^2, a^3, a^4 designate the four cylinders and b^1, b^2, b^3, b^4 , the four hollow pistons of them. The said four cylinders are arranged independently and connected to each other in a solid manner. Each of the four pistons carries a pair of lugs c^1, c^2, c^3, c^4 , which are connected through lateral slots of the corresponding extension of the cylinder to a connecting rod m passing through. The lugs c^4 , besides, are linked to the forked connecting-rod d , which is engaged by the unique crank f of the fly-wheel shaft.

By means of the distribution (not shown) of the motor the single stages of the working

order are distributed among the four cylinders. The several cylinders are arranged in pairs opposite to each other in such a manner to make the working stroke impart motion to the crank f for once and the return stroke impart it again through the connecting-rod m .
60

According to the arrangement shown in Fig. 4 of the drawings the cylinder a^4 , for instance, could perform the exhaust-stage, 65 the cylinder a^3 the compressing stage, the cylinder a^2 the working or exploding stage and the cylinder a^1 the suction stage.

Into the four hollow pistons the four hollow open-worked displacers h^1, h^2, h^3, h^4 are 70 made to extend, said displacers being fixed to the plates i^1, i^2, i^3, i^4 , secured to the extensions of the cylinders. By inserting a laterally open-worked box s between each pair of cylinders a^1, a^2 , and a^3, a^4 , I have 75 provided the means of giving the air access to the displacers. For the rest I have also placed laterally open-worked boxes t between the cylinders a^2 , and a^3 , placed opposite to each other with their closed ends, 80 in order to allow the air to enter into contact with the cylinder-bottoms, as it is advantageous to cool not only the inside of the pistons but also their outside surface as completely as possible by copious contact with 85 the air. The outside surface of the cylinders, of course, is constantly cooled by the access of the atmosphere.

I claim as my invention:

1. A combustion motor comprising a multiplicity of cylinders, a hollow piston for each cylinder open to the atmosphere, a single connecting-rod connected to said pistons, and means projecting into the hollow space of the pistons to partially obstruct the same. 95

2. A combustion-motor comprising four cylinders, each of said cylinders having a hollow piston open to the outside and each piston being provided with a stationary displacer of the air, said pistons being all connected to a single connecting-rod laterally linked to said pistons and working on a single crank. 100

In testimony whereof I have affixed my signature in presence of two witnesses.

DR. RUDOLF KRONENBERG.
